UNITED STATES PATENT OFFICE.

AUGUSTUS P. DAVIS, OF PITTSBURG, PENNSYLVANIA.

DESIGN FOR A BUTTON.

SPECIFICATION forming part of Design No. 18,740, dated November 20, 1888.

Application filed August 13, 1888. Serial No. 262,654. Term of patent 14 years.

To all whom it may concern:

Be it known that I, AUGUSTUS P. DAVIS, a citizen of the United States, residing at Pittsburgh, in the county of Allegheny and State of Pennsylvania, have invented and produced a new and original Design for a Button, of which the following is a specification, reference being had to the accompanying drawing, forming a part thereof.

10 My invention relates to a design for buttons; and it consists in the representation of a shield, crossed swords extending across it, the wreath, the figures of the soldier and sailor, the flags, the muskets, and the cannon, as will be more 15 fully described hereinafter.

The drawing is a front view of my newly-designed button.

The central part or portion of the design is in the form of a shield, which has a border of 20 peripheral scroll-work. A transverse bar divides the face of the shield. Above the bar appears the representation of a rising sun half above the horizon, in the center of which appear letters in the form of a monogram. Below the said transverse bar appear two sabers 25 crossed, with points upward through a laurel-wreath, the background being studded with stars. On the right-hand or dexter side of the shield appears the representation of a soldier 30 dressed in the military fatigue-uniform of the Government of the United States in use from the year 1861 to 1865, with waist and cross-belts, and standing on a platform or support, his right hand resting on the upper part of the 35 shield. In the background and behind and to the right of the soldier are arranged and ap-

pear flags, muskets, and cannon. On the left-hand or sinister side of the shield appears the representation of a sailor dressed in the naval uniform of the Government of the United States in use from the year 1861 to 1865, and standing on a platform or support, his left hand resting on the upper part of the shield. In the background and behind and to the left of the sailor are arranged and appear flags, 45 muskets, and cannon. Directly below and to the right and left of the shield appears an ornamental scroll, which contains between its upper and lower lines three spaces for an inscription. Directly above the shield and 50 slightly separated from it appears a crest consisting of a roll divided into equal parts and with rounded ends. On this roll rests a support consisting of rocks or other substances, and on them an American eagle. Above the 55 eagle appears an ornamental scroll containing within its upper and lower lines a space for an inscription. The scrolls and the eagle form no necessary part of this design, for they may be used or not, as may be preferred.

What I claim is—

The design for a button, consisting of the representation of the shield, the crossed swords and laurel-wreath thereon, the figures of the soldier and sailor upon opposite sides of the shield, and the flags, muskets, and cannon, as shown.

AUGUSTUS P. DAVIS.
